US00D859812S

(12) **United States Design Patent** (10) **Patent No.:** **US D859,812 S**
(45) **Date of Patent:** ** *Sep. 17, 2019

(54) **BAG**

(71) Applicant: **YETI Coolers, LLC**, Austin, TX (US)

(72) Inventors: **Roy Joseph Seiders**, Austin, TX (US);
Dustin Bullock, Austin, TX (US)

(73) Assignee: **YETI Coolers, LLC**, Austin, TX (US)

(*) Notice: This patent is subject to a terminal disclaimer.

(**) Term: **15 Years**

(21) Appl. No.: **29/660,134**

(22) Filed: **Aug. 17, 2018**

(51) **LOC (12) Cl. 03-01**

(52) **U.S. Cl.**

USPC **D3/201**

(58) **Field of Classification Search**

(57) **CLAIM**

The ornamental design for a bag, as shown and described.

DESCRIPTION

The file of this patent contains at least one drawing executed in color. Copies of this patent with color drawings will be provided by the Office upon request and payment of the necessary fee.

FIG. 1 is a top, front, left perspective view of a bag showing our new design;

FIG. 2 is a front view thereof;

FIG. 3 is a rear view thereof;

FIG. 4 is a left side view thereof;

FIG. 5 is a right side view thereof;

FIG. 6 is a top, front, left perspective view of an alternative claimed configuration of a bag showing our new design;

FIG. 7 is a top, front perspective view thereof;

FIG. 8 is a top, front, left perspective view of an alternative claimed configuration of a bag showing our new design; and,

FIG. 9 is a top, front perspective view thereof.

The portions of the bag shown in broken lines form no part of the claimed design.

**1 Claim, 9 Drawing Sheets
(9 of 9 Drawing Sheet(s) Filed in Color)**
